CLAIM

The ornamental design for the stand for portable computer, as shown and described.

DESCRIPTION

FIG. 1 is a perspective view of the stand for portable computer in the compact configuration;

FIG. 2 is a front elevational view of the stand for portable computer shown in FIG. 1;

FIG. 3 is a rear elevational view of the stand for portable computer shown in FIG. 1;

FIG. 4 is a right side elevational view of the stand for portable computer shown in FIG. 1;

FIG. 5 is a top plan view of the stand for portable computer shown in FIG. 1;

FIG. 6 is a bottom plan view of the stand for portable computer shown in FIG. 1;

FIG. 7 is a perspective view of a second embodiment of the stand for portable computer in the compact configuration;

FIG. 8 is a front elevational view of the stand for portable computer shown in FIG. 7;

FIG. 9 is a rear elevational view of the stand for portable computer shown in FIG. 7;

FIG. 10 is a right side elevational view of the stand for portable computer shown in FIG. 7;

FIG. 11 is a top plan view of the stand for portable computer shown in FIG. 7;

FIG. 12 is a bottom plan view of the stand for portable computer shown in FIG. 7; and,

FIG. 13 is a perspective view of the stand for portable computer shown in FIG. 1 but in the extended configuration.
